UNITED STATES PATENT OFFICE

124,845

DESIGN FOR A PHOTOGRAPHIC COPYING APPARATUS

Alvin E. Schubert, Rochester, N. Y., assignor to Eastman Kodak Company, Rochester, N. Y., a corporation of New Jersey

Application June 20, 1940, Serial No. 93,146

Term of patent 14 years

To all whom it may concern:

Be it known that I, Alvin E. Schubert, a citizen of the United States, residing at Rochester, in the county of Monroe and State of New York, have invented a new, original, and ornamental Design for a Photographic Copying Apparatus, of which the following is a specification, reference being had to the accompanying drawings, forming part thereof and in which:

Fig. 1 is a front perspective view of a photographic copying apparatus, showing my new design, and

Fig. 2 is a side elevation of the same.

I claim:

The ornamental design for a photographic copying apparatus, as shown.

ALVIN E. SCHUBERT.
